UNITED STATES PATENT OFFICE

NICHOLAS MARCALUS, OF ELIZABETH, NEW JERSEY, ASSIGNOR TO AUTOMATIC PAPER MACHINERY CO. INC., A CORPORATION OF NEW JERSEY

BOX FOR DISPENSING ROLLED PAPER

Application filed June 10, 1929. Serial No. 369,573.

This invention relates to boxes or dispensing packages for rolls of paper of the general character described in my Patent No. 1,630,495. The box of that patent is a relatively long cardboard container designed to enclose a roll of paper wound upon a cardboard core, the free edge of the front wall being provided with a metal strip having a serrated cutting or tearing edge. The paper is drawn from the roll while the latter is held in the box, and torn along the serrated edge when the desired length has been unrolled. During this operation the top of the box is preferably closed with its flap tucked behind the front wall, the latter with the flap forming a guideway for the paper. As the roll is not tightly held within the box, particularly after a substantial quantity of paper has been unrolled, it frequently happens that, between times, the roll turns, pulling the forward end of the paper into the box, so that when the user, commonly a housewife, wishes to tear off another sheet she cannot easily reach the paper but must first raise the cover of the box, pull the forward end of the roll beyond the cutting edge, and then close the cover, reinserting the flap behind the paper.

It is the object of the present invention to provide means for preventing the forward end of the paper from slipping back into the box so that the roll is always in readiness for use. I attain this object by inserting a yieldable spacing element between the front of the box and the roll, so shaping this element that it shall always press against the roll and prevent free turning thereof as long as any paper remains on the core. The cover flap is preferably inserted between the roll and the forward end of the paper so that the latter is pinched between the spacing element and the flap and can move only when pulled by one using the package in the intended manner.

In the accompanying drawing I have illustrated certain preferred embodiments of my invention. In these drawings, Figure 1 is a transverse section through a box constructed in accordance with the present invention and showing a roll of paper in

place with the forward end of the sheet extending from the box in position for unwinding; Figure 2 is a view similar to Figure 1, but showing the same roll with most of the paper unwound; Figure 3 is a perspective view showing the yieldable spacing element in position for assembly; Figure 4 is a detail in perspective showing the manner in which the spacing element is held in position on the front wall of the box; and Figure 5 is a section similar to Figure 1 showing a modified method of securing the spacing element in place.

The box illustrated is an elongated rectangular cardboard box substantially square in cross-section comprising a front side wall 1, a rear side wall 2, a bottom 3 and a top or cover 4, and designed to hold a roll of paper 5, such as a roll of wax paper, commonly used by housewives for wrapping food, wound upon the usual cardboard core 6. The front wall 1 of this box is provided along the inner face of its upper edge with a metallic strip 7 having a serrated cutting edge along which the paper is torn after the desired quantity has been unrolled. The foregoing constitutes, in general, the construction of the box illustrated in Patent No. 1,630,495 and I shall now describe the improvements therein which constitute the present invention.

Inserted between the front wall 1 and the roll is a yieldable spacing element 8 consisting of a strip of cardboard longitudinally scored at 9 so that it can be readily bent along the line of the score. This spacing element is held in place between the bottom of the box and the bottom edge of the metallic strip 7 which is upturned at 11 to form an anchorage for the upper edge 90 of the spacing element. The lower edge of the spacing element is held against the front wall by means of tabs 12 cut from the bottom of the box and turned upward as clearly illustrated in Figure 4.

The cover 4 of the box is of less width than the bottom and is provided along its forward edge with a depending flap 13 which extends downward to a point below the center of the roll. This flap 13 and the

spacing element 11 constitute between them a passageway for the paper as it is unwound from the roll.

The dimensions of the spacing element are such that it always bears against the roll as long as any paper remains upon it, as will be evident from a comparison of Figures 1 and 2, and this pressure is sufficient to hold the roll snugly against free rotation so that the position of the roll is not unintentionally changed during times when paper is not being unwound. The pressure between the flap and the spacing element is also sufficient to hold the paper frictionally between them. This friction is insufficient to interfere with the unwinding of paper in using the package, but it is sufficient to prevent any movement of the forward end of the paper during times when the package is not in use. As a consequence, the package is always available for use and the housewife is not put to the inconvenience of opening the box and threading the forward end of the paper between the flap and the front wall of the box.

The package is assembled by first placing the roll within the box, inserting the flap between the body of the roll and the forward end of the paper, which is drawn forward slightly for this purpose, and then inserting the spacing element between the roll and the front wall of the box, tucking its upper edge under the upturned edge 11 of the cutting strip and anchoring its lower edge in position by bending the tabs 12 upward.

In Figure 5 I have illustrated a slightly modified means for anchoring the upper edge of the spacing element in position. Instead of upturning the lower edge of the metallic strip 7 I cut a plurality of tabs 14 in the front wall of the box and bend them inward as illustrated. The upper edge of the spacing element is then tucked under these tabs and so held in position.

I claim:

1. A box for dispensing roll paper, comprising side walls and bottom, a metallic cutting strip secured to the top inner face of the front side wall, an upturned lower edge on said strip and a spacing element of flexible material inserted between the front wall and the roll with its edges bearing against the bottom of the box and the upturned lower edge on the cutting strip and with its mid portion bowed in to press against the roll and prevent free turning thereof.

2. A box for dispensing roll paper comprising side walls and a cover, a depending flap on the cover, and a yieldable spacing element inserted between the front side wall and the roll, the flap and spacing element gripping between them the forward end of the paper to prevent its slipping back into the box.

3. A box for dispensing roll paper comprising side walls, a bottom, and a cover of less width than the bottom, a yieldable spacing element inserted between the front side wall and the roll and bearing against the roll to prevent free turning thereof, a flap depending from the forward edge of the cover and extending between the roll and the spacing element, the flap and spacing element forming a guideway for the paper as it is unwound.

4. A box for dispensing roll paper comprising side walls, a bottom, and a cover of less width than the bottom, a cutting edge along the top of the front wall, a strip of cardboard, longitudinally scored between its edges, mounted on the inside of the front wall between the cutting edge and the bottom, bent along the score and bowed inward and a flap depending from the forward edge of the cover and extending below the score on the cardboard strip, the arrangement of the parts being such that a roll of paper in the box is held snugly against free rotation and the paper as unwound passes between the flap and the cardboard strip and is held against unintended movement.

In testimony whereof I affix my signature.
